LOADING DEVICE FOR REFRIGERATED
STORAGE COMPARTMENTS

Samuel Bohn, Nutley, N. J.

Application December 21, 1950, Serial No. 201,918

4 Claims. (Cl. 312—310)

1

This invention relates to refrigerated display cabinets, and more particularly, to the storage compartments thereof, by which is meant the lowermost portion of refrigerated display compartments. This lowermost portion or base has one or more doors giving access to the lower storage space, such doors being sufficiently large to permit passage of cases, either wooden or metal cases or large cartons of corrugated board or the like. It is the practice in food stores to place quantity or case lots of the various commodities displayed and vended, in the storage compartment of the cabinet, and to replenish the display shelves and bins from the case lots kept in the storage compartment.

The expression "refrigerated display cabinet" is used generically to include all types of such cabinets, such as: refrigerated cabinets having shelves and maintained in refrigerated condition by doors, either hinged or sliding, which must be opened to reach the food or beverage displayed or kept on the shelves; refrigerated cabinets in which the goods are placed in bins or compartments accessible from above after opening the doors (usually sliding doors) which normally close the top of the bins against refrigeration loss; refrigerated cabinets having similar open top bins or compartments but not provided with doors or the like. The foregoing is not intended as an exhaustive enumeration of the various types of "refrigerated display cabinets" to which this invention pertains. It is sufficient to state that the invention relates to all refrigerated display cabinets which have a lower storage compartment as described above.

One of the objects of the invention is to provide means for facilitating the loading of cases or cartons into the storage compartment of refrigerated display cabinets, and the withdrawal of such cases or cartons (which are frequent occurrences in the constant replenishing of the display compartments, as explained above). Another object of invention is to provide means for protecting the sides and bottom of the door opening against injury by the cases as they are loaded into, or withdrawn from, the storage compartment. Still another object of the invention is to provide an improved door for storage compartments of refrigerated display cabinets which will not present, when open, an obstacle or hindrance in front of the storage compartment as in the case with the doors as heretofore used.

For the attainment of the foregoing and such other objects of invention as may appear or be pointed out herein, I have shown a preferred em-

2

bodiment of my invention in the accompanying drawing, wherein:

Fig. 1 is a perspective view of a refrigerated display cabinet, the storage compartment of which is provided with the improved doors, one of which is shown in open position;

Fig. 2 is a sectional elevation taken on the line 2—2 of Fig. 1;

Fig. 3 is a sectional elevation similar to Fig. 10 2 but showing the door in closed position;

Fig. 4 is a horizontal sectional view taken on the line 4—4 of Fig. 2;

Fig. 5 is a sectional elevation (similar to Figs. 15 2 and 3) but showing the invention applied to sliding doors, rather than hinged doors (as in Figs. 1-4);

Fig. 6 is a sectional elevation similar to Fig. 5, but showing the sliding doors closed; and

Fig. 7 is a horizontal sectional view taken on the line 7—7 of Fig. 5.

The refrigerated display cabinet shown in Fig. 1 is of the type described in the foregoing statement of invention having a display compartment 25 open or accessible at the top, which may or may not be provided with sliding doors, and which is usually partitioned into a plurality of bins (not shown). This type of refrigerated display cabinet has been shown merely for facility of illustration, it being apparent, as explained in the 30 statement of invention, that the invention is applicable to any type of refrigerated display cabinet so long as it has a lower storage compartment such as is indicated in Fig. 1 and designated 2.

Storage compartment 2 is shown in Fig. 1 as having three doors 3, one of which is in open position. The doors are sufficiently large to permit passage of quantity-lot cases which, as explained in the statement of invention, are kept 40 in storage compartment 2 for constant replenishment of the display bins 1, or display shelves, etc., depending upon the type of refrigerated cabinet.

It should be noted from the open door of Fig. 1 45 that the improved storage doors open upwardly, being hinged at the top of the door opening. In refrigerated display cabinets as heretofore made the doors to the storage compartment are hinged at one or the other side of the door opening so that they open outwardly or extend forwardly at the front of the cabinet. When it is realized that the cabinet may have a number of storage doors and that the quantity-lot cases 50 are of considerable size and weight, it will be evident that the opening of one or more storage

doors (usually all are opened to ascertain the proper arrangement of the cases and cartons within the storage compartment) will present obstacles to free movement of the cases in front of the cabinet. In the improved arrangement of Fig. 1, the entire front of the cabinet is free and clear of any obstacles even when all the storage doors are opened. By reason of their being hinged at the top of the door opening, the improved doors when opened upwardly occupy a position which is entirely away from the floor space in front of the cabinet, which is thus left free and clear for movement of the cases or cartons.

The improved hinge arrangement is shown in detail in Figs. 2 and 3, wherein the rear wall of storage compartment 2 is designated 4; the floor 5, and the roof 6. The top or lintel of the door opening is designated 7 and the bottom or saddle is designated 8. One half 17 of the hinge is secured to lintel 7 while the other half 13 of the hinge is secured to door 3; the hinge pin is designated 12. The door is shown in Fig. 2 in its open position. There also is shown in Fig. 2 two accessories of the present invention, namely, a shield 30 for protecting the sides of the door opening and an inclined plate 20 for facilitating movement of the cases or cartons. Both the protective shield 30 and the inclined plate 20 will be fully described subsequently. But attention is called to them at this time because as shown in Fig. 2, the side shield 30 and the bottom plate 20 occupy positions within the door opening which would prevent closing of door 3. As will be more fully described subsequently, the side protective shield 30 and the inclined plate 20 are turned from their operative positions shown in Fig. 2 to inoperative positions within the storage compartment, see Fig. 3, preparatory to closing the door. Door 3 can then be sealed tight, as shown in Fig. 3, with its distal side abutting saddle 8 of the opening, and held closed by door lock 9.

The aforesaid inclined plate 20 extends the full length of the door opening, see Fig. 4, between the side jambs thereof. In Fig. 4 is shown the door at one end of storage compartment 2, the end wall thereof being designated 11. The door jamb at end wall 11 of the storage compartment is designated 15, and one of the medial door jambs (partially shown in Fig. 4) is designated 16. Referring to Fig. 2, inclined plate 20 extends from the inside edge of door saddle 8 outwardly, with its outer edge 21 resting on the floor. Saddle 8 is inclined downwardly from its inner edge, so that plate 20 takes the angle of inclination of the saddle. At the inner edge of door saddle 8, inclined plate 20 is bent downwardly to present a narrow flange 28, which forms part of a hinge 18. The other part of hinge 18 is a narrow strip 19 which is secured to the inside wall of saddle 8. Inclined plate 20 (including its narrow flange 28) may thus be turned about hinge pin 18 from its operative position, Figs. 2 and 4, to its inoperative position within storage compartment 2, see Fig. 3. In the latter position, inclined plate 20 clears door saddle 8, so that door 3 may make a tight closure therewith, as shown in Fig. 3.

Inclined plate 20 has one or more openings 22 (three being shown, by way of example, in Fig. 4) through which project the upper portions of rollers 23 rotatively mounted at the underside of inclined plate 20, as indicated by shaft pin 24, Fig. 4. Heavy cases and cartons may thus be pushed into, and pulled out of, storage compart-

ment 2, by means of inclined plate 20 and its rollers 23. Inclined plate 20 serves another function in protecting the door saddle 8 when in operative position, as in Fig. 2.

The protective shields 30, mentioned above, protect the door jambs against injury by the cases as they are moved into and out of the storage compartment. Referring to Fig. 4, there is a protective shield 30 at each of the two door jambs 15, 16. Protective shield 30 is bent at the inner edge of the door jambs to provide a flange 38 which forms part of a hinge 37. The other part of the hinge is a narrow strip 39 which is secured to the inside wall of the door jambs 15, 16. The outer edge of shield 30 is bent back slightly to form a lip 36 which protects the outer edges of the door jambs, as clearly shown in Fig. 4. In the latter position, the two protective shields are in operative position (see also Fig. 2). The shields 30 may be turned on their hinge pins 37, to an inoperative position within the storage compartment, see Fig. 3, so that door 3 may be closed, as shown in that figure.

Inclined plate 20 and the pair of protective shields 30, 30 have been shown in Figs. 1-4 as applied to storage compartments having hinged doors. They may be similarly applied to storage compartments having sliding doors, as in Figs. 5-7, wherein their frames, have been given reference numerals similar to that of Figs. 1-4. It should be noted that door saddle 8 and lintel 7 (Figs. 5 and 6) and door jambs 15, 16 (Fig. 7) are not beveled as in Figs. 1-4 but are square. The sliding door frame 40 is fitted securely around the door opening, more particularly, the door saddle 8 and lintel 7 (Figs. 5-6) and door jambs 15, 16 (Fig. 7). Frame 40 has two sets of runners 41, 42 the first for an inwardly-disposed sliding door 43 and runners 42 for an outwardly-disposed sliding door 44. Sliding doors 43 and 44 are substantially half the length of the door opening so that when slid to one side, as in Fig. 7, the other half of the door is open.

As best seen in Fig. 7, the sliding door opening is provided with two inclined plates 20, 20 each substantially half the length of the door opening. When the two doors 43, 44 are slid to one end of the opening, the inclined plate 20 at that end of the opening is in inoperative position behind the pair of sliding doors, as shown. The other inclined plate 20 may be turned to operative position, projecting through the opening at the other end, as shown. Likewise, two protector shields 30, 30 are provided. The one at the door jamb (16, Fig. 7) towards which the two doors have been slid is in inoperative position behind the doors, as shown. The other protective shield 30, at door jamb 15, is in operative position, protecting that side of the door opening at which inclined plate 20 is disposed in operative position.

The inclined plate used with the hinged door (Figs. 1-4) is straight from outer edge 21, see Fig. 2, to the inside edge of door saddle 8, where it is bent to form flange 28. On the other hand, the inclined plate used with the sliding doors (Figs. 5-7) is straight from outer edge 21, see Fig. 5, only to the outside edge of door saddle 8. The portion of plate 20 between the outside edge of the door saddle to the downwardly-bent flange 28 is bent slightly, as indicated at 25, Fig. 5, to provide a horizontal portion which rests upon the runners 41, 42 of the sliding door frame.

I claim:

1. In a storage compartment for a refrigerated display cabinet having a door opening spaced

from the bottom of the compartment floor by a saddle, in combination, an inclined plate having an outer edge rested on the floor in front of the cabinet, the inner edge portion of the inclined plate being bent at the inner edge of said saddle to present a narrow flange, and a strip secured to the inside wall of said saddle close to the floor of the compartment, said narrow flange and strip forming a hinge whereby the inclined plate may be turned to operative position extending through the door opening or to inoperative position within the compartment.

2. The combination according to claim 1 for a storage compartment having a hinged door and wherein said saddle is inclined downwardly from its inside edge, said inclined plate being substantially the length of said door opening and extending as a straight plate from said inner edge of the saddle and having an angle of inclination equal to that of the saddle.

3. The combination according to claim 1 for a storage compartment having a pair of sliding doors and wherein said saddle is square, provided with a pair of inclined plates each substantially half the length of said door opening, each plate being inclined from the outer edge

of the saddle to the floor, the portion between the outer edge of the saddle and said plate flange being bent to rest horizontally above the saddle.

4. The combination according to claim 1 wherein said inclined plate is provided with at least one opening, a roller rotatively mounted to the underside of the plate with the upper portion thereof extending through said opening.
